AUTOMATIC PRINTING TELEGRAPH EX-
CHANGE SYSTEM

Gilbert S. Vernam, Hackensack, N. J., assignor to
Postal Telegraph-Cable Company (New York),
New York, N. Y., a corporation of New York

Application February 20, 1937, Serial No. 126,769

16 Claims.

(Cl. 178—2)

My invention relates in general to printing telegraph systems and more particularly to automatic printing telegraph exchanges and concentrator circuits for interconnecting subscribers' stations to the central office operators' stations.

In automatic printing telegraph exchange systems heretofore in use of the type employing single wire subscribers' lines, special apparatus has been necessary at the subscribers' stations, due to the fact that, in general, the automatic system works with a normal low line current whereas in the manual concentration systems the line current is normally much higher. One of the objects of my invention is to provide a line relay circuit at the central office which permits operation with either normal high line current or normal low line current, thus permitting the same type of subscriber's station apparatus to be used interchangeably with either manual or automatic concentration systems, and also permitting the same type of central office equipment to be used interchangeably with either the standard "high line current" subscriber's apparatus or with the special "low line current" subscriber's apparatus.

It is a further object of my invention to reduce the number of automatic switches otherwise required, by establishing direct semi-permanent connections between certain subscribers' lines and central office printers during periods of heavy traffic.

It is a further object of my invention to apply the relay circuit to automatic concentrators or printer exchanges of various sizes and also for operating calling signals and controlling the motors of direct connected printers.

Accordingly one of the main features of my invention is the provision of a line relay and a cut-off relay in each subscriber's line at the central office, so arranged that an inward call can be initiated either by increasing a normally low line current or by first decreasing and then increasing a normally high line current.

Another feature of my invention is the provision of separate printer sets at the central office which may be plugged directly into a subscriber's line, during periods of heavy traffic, without extending the connection through the automatic switches usually employed in establishing connections with subscribers' stations.

Still another feature is the provision of relays associated with the separate central office printer sets for the purpose of operating a calling signal and automatically starting the printer motors of both the central office and subscriber's station

printers when a call is made in either direction.

Other features of my invention will be apparent from the following description, as well as from the appended claims.

The preferred embodiment of my invention is illustrated in the accompanying drawings, in which

Fig. 1 illustrates a high current subscriber's station of the type usually used with manual concentrators connected to line and cut-off relays at a central office adapted for use as part of a hundred line automatic concentrator,

Fig. 2 diagrammatically indicates the remainder of the apparatus constituting a hundred line automatic concentrator, including the central office operator's printer,

Fig. 3 illustrates a subscriber's station of the usual automatic or normal low current type adapted to be connected with the same type of line and cut-off relays at the central office,

Fig. 4 illustrates a circuit similar to that shown in Fig. 1 but adapted to a thousand line automatic concentrator or printer exchange system,

Fig. 5 illustrates diagrammatically further apparatus at the central office for cooperation with the circuit of Fig. 4,

Fig. 6 illustrates the normal low current subscriber's station for connection with the thousand line concentrator or printer exchange system, and

Fig. 7 illustrates a circuit arrangement of the printer set for tabling busy lines.

In the drawings the same reference characters are generally used to show similar apparatus in the various figures.

Referring now to Figs. 1 and 2, the numeral 1 indicates generally a subscriber's station connected through a line 3 to the central office line relay circuit designated generally as 5. This circuit is associated with the central office apparatus illustrated generally in Fig. 2. The particular apparatus used in the central station may be of any desired type and as it does not form a part of this invention it accordingly is shown in Fig. 2 merely in block diagrams. A particular example of such apparatus is shown in my Patent 1,910,867 issued May 23, 1933.

A more particular description of the circuit shown in Figs. 1 and 2 follows.

Normally a relatively high current, for example, about 50 milliamperes flows from negative battery 10 at the central office through the upper winding of cut-off relay 11, jack 200, resistance R, back contact B of line relay 23, front contact A of cut-off relay 11, line 3 through the winding of polar relay 17, winding of motor control relay 55

39, armature and front contact A of polar relay 17, through calling key 21 to ground at the subscriber's station. This holds cut-off relay 11 and polar relay 17 energized. Equalizing resistors R are provided in each subscriber's line to enable adjustment to correct for differences in line resistance. To call from a subscriber's station, the calling key is depressed and released, thus opening and closing the line. When the line is opened cut-off relay 11 releases, and when the line closes line relay 23 operate through back contact B of cut-off relay 11. Polar relay 17 and control relay 39 at the subscriber's station release when the line is opened and are again reenergized upon closing of the line but this has no effect except to start and momentarily run the motor 41 during the interval while the line is open at calling key 21. The printer cannot be operated, however, as its circuit is open while key 21 is depressed and it is short-circuited immediately through contact A of polar relay 17 when key 21 is released. This short-circuit prevents the subscriber from sending during the interval while motor 41 is running, but slowing down immediately after key 21 is released. Without this short-circuit, it would be possible for the subscriber to send signals from his printer keyboard which would vibrate relay 39 and cause motor 41 to continue to run. Such signals would not be properly received at the central office as the central office printer is not yet connected to the line and might result in lost messages. With the cut-off relay 11 released and line relay 23 operated, relay contacts 22 and 24 are closed and ground is applied to the test bank terminals T of the finder connectors, and slow operating group relay 25 operates to close switch 27 grounding start lead 29 of the idle position locator or allotter 31, causing the first idle finder connector 33 to find the calling line and to connect it to operator's set 35. When the finder connector cuts in on the calling line, ground is applied to the "private bank" terminal P energizing the lower windings of relays 11 and 23 in series by battery 37. This operates to lock line relay 23 in its operated position and operates cut-off relay 11 which removes the ground previously applied to the test bank terminal T and relay 25 and extends the calling line through front contacts A of relays 11 and 23, and the line bank terminal L, which is now connected to the central office printer. Current from a positive battery associated with the central office printer set 35 causes the subscriber's station polar relay 17 to release, shorting out motor control relay 39 through back contact B, causing it to release, and starting printer motor 41. This also permits the line current to traverse printer keyboard and magnet 43 by removing the short circuit. Messages may now be transmitted between the subscriber's station and the central office. Polar relay 17 remains released, with its armature against back contact B during the transmission of printer signals, as the armature is held against B by a spring (not shown) when the circuit is open and is held against the same contact by current from the positive battery when the circuit is closed.

When the idle finder connector switch 33 and its associated printer set 35 were first selected by the allotter 31, the dial lead of set 35 was momentarily grounded by the allotter, thus operating relay 55, which locks itself through release key 56. Ground from release key 56 over dial lead 58 serves to hold the finder connector switch 33 to prevent it from releasing. After the message

has been transmitted by the subscriber and acknowledged by the central office operator, the connection may be released from the central office in the usual way, the operator depressing his release key 56 which releases relay 55 and removes the holding ground from the dial lead allowing finder connector switch 33 to release. The release of the finder connector removes ground from the private bank terminal P. This releases line relay 23 immediately but cut-off relay 11 is made to be slow releasing and remains operated until the line relay 23 has released and closed the line circuit through the upper winding of cut-off relay 11, so that the control relay remains operated and the circuit is restored to its normal idle condition. Current from negative battery 10 operates polar relay 17, removing the short circuit from control relay 39 to stop the printer motor at the subscriber's station.

Turning now to Fig. 3 in connection with Figs. 1 and 2, the operation of the system with subscribers' stations arranged for normal low current lines will be described.

With this system the line 3 normally carries a very low current, for example, about six milliamperes which is not strong enough to operate cut-off relay 11 and therefore it is normally released. Likewise the low current is insufficient to operate line relay 23. The polar relay 51 at the subscriber's station (Fig. 3) is provided with two windings, winding 53 of high resistance, and winding 55 of low resistance. Operation of calling key 57 functions to short circuit high resistance winding 53 of polar relay 51 and the line current from battery 10 at the central station is increased to a value sufficient to operate line relay 23. This grounds the test bank terminals and operates group relay 25 causing the line to be switched through to the central office operator's printer set in the same manner as described in connection with Fig. 1. Current from the positive battery at the central office causes the station polar relay 51 to release thus operating control relay 39 and starting printer motor 41. The calling key should now be restored to its normal position since the control relay contacts shown at 59 now shunt the high resistance winding of polar relay 51. Connection is now established between the subscriber's station and the operator's station. The release circuit for the system shown in Fig. 3 is in general substantially the same as that in Fig. 1, however this difference occurs. After line relay 23 has released, and the polar relay 51 at the subscriber's station has released, the line current reduces to the normal low current value since the shunt is removed from winding 53 and thus allows cut-off relay 11 to release, restoring the circuit to its normal unoperated position.

Outward calls from the central office to the subscribers are handled substantially in the same manner as in the previously constructed circuits, i. e. the central office operator operates a dial to cause the finder connector associated with her set to step its wipers to the terminals of the desired customer's line, to test the line to determine whether it is busy, and if not busy to connect with the bank terminal of the line. When the finder connector 33 grounds the private bank terminal P of the called line, the lower windings of line relay 23 and cut-off relay 11 are energized. In the circuit as shown in Fig. 1 the cut-off relay remains operated and the line relay operates. This connects through to the subscriber's station and starts his motor. With the low current line, both line relays 23 and 75

5 cut-off relay 11 operate upon grounding of the private bank terminal, resulting in a through line connection and the starting of the printer motor. In the low current station system, the line relay 23 may operate slightly faster than the cut-off relay 11 in which case a short impulse of current will be sent through group relay 25. In order to prevent such a short impulse applied to relay 25 from falsely starting the position selector on outward calls, relay 25 is made slow operating, so that it will not respond to such short pulses.

10 The system shown in Figs. 4, 5 and 6, is applicable to a thousand line automatic concentrator or printer exchange system. This may be any type of concentration system including systems in which separate groups of operators' printers are used at the central station for inward and outward calls such as illustrated in my prior Patent No. 1,895,113 issued on January 24, 1933, and further may be connected to an exchange system which permits each subscriber to communicate through a tollboard with other systems or through repeater control with other subscribers in a manner, for example, such as described in the patent to F. G. Hallden, No. 1,895,097, issued January 24, 1933. The system generally, as shown in these figures, is broadly the same as that shown in Figs. 1 and 2 so a detailed description only will now be given.

15 The private bank terminals of line finders in these thousand line concentrators are open when the corresponding line is idle, grounded when busy and connected to battery when the line is calling. In answering an incoming call the line finders hunt for battery on the private bank terminals instead of hunting for a ground on separate test bank terminals, as in the case of the hundred line combination finder connector, described above. For this reason the line relay 23 is wired so that, when operated, it connects the battery through its own winding and that of the cut-off relay 11 to the private bank terminals P. Except for this change in wiring the relay circuit shown in Fig. 4 is substantially the same as that shown in Fig. 1.

20 Since this concentration and exchange system may provide for selective service as set forth in the above patents referred to, dial 101 has been shown in connection with the subscriber's station, in Fig. 5. However, the system could be used without the dial if this selective service is not required, in which case the subscriber's station circuit of Fig. 1 would be used in connection with the line and cut-off relays of Fig. 4.

25 At the subscriber's station, as shown in Fig. 4, a calling dial 101 is shown and a milliammeter 103 is provided in the line. Printer magnet coils 43 are normally short circuited by the make or front contact A of polar relay 17 and conductor 19 to permit operation over longer lines without a detrimental decrease in the normal current due to resistance in the printer contact. This short circuit also serves to prevent false starting of the printer motor before the call is completed. To make a call, calling key 21 is depressed and released thus releasing cut-off relay 11 and operating line relay 23 and causing the line finder 105 to connect the line through 30 to a selecting circuit. As the line relay of the selecting circuit and its battery tap resistor are of lower resistance than the winding of the cut-off relay 11 and its battery tap resistor, the line current now increases. This increase may be 35 observed in meter 103 indicating that the call-

ing station may dial. The off normal contacts 102 of the dial 101 are arranged to connect a local negative potential from battery 107 to the line and prevent the printer motor 41 from starting in response to the dial pulses. The dial of the subscriber's station may now be operated to actuate the switch of the selecting circuit to select the class of service required. Assuming that the subscriber called in order to send a telegram, the digit dialed will be such that a group 10 of secondary line finders associated with central office operators' printers will be selected. The first idle secondary finder 109 of this group will operate to extend the line through to operator's printer set 111. When the line is switched 15 through to the central office printer, the line current reverses, polar relay 17 releases, thus removing the short circuit from the printer magnet 43, short circuiting control relay 39 through back contacts of the polar relay, thus starting 20 printer motor 41. The circuit is now established for the subscriber to transmit his message. After the desired communication has been concluded the circuit is released in the same manner as that described in connection with Fig. 1.

25 In the low current system as shown in Fig. 6, the line circuit normally extends through both the high and low resistance windings 53 and 55 respectively, of polar relay 51, through a calling key designated generally as 113 and through a 30 back contact 115 of control relay 39 to ground. The high resistance winding 53 limits the line current to a low value, for example about six milliamperes, such that cut-off relay 11 (Fig. 4) releases and line relay 23 does not operate. Polar relay 51 will operate on this low current however. When the calling key is operated it connects dial lamp 117 and its shunt resistance across the high resistance winding 53 of polar relay 51 and removes the short circuit from the 40 dial pulsing contacts by opening contacts 118. The line current now increases from the normal value up to a higher value, for example about forty milliamperes. The increased line current operates line relay 23 (Fig. 4) and causes the 45 circuit to be switched through the line finder 105 to the selecting circuit 107 (Fig. 5). The line current now increases to a higher value, for example about sixty milliamperes, and the dial lamp 117 lights up indicating that the circuit is 50 ready for dialing. The off normal contacts 119 of the dial 101 open the windings of control relay 39 to prevent starting of the motor even though polar relay 51 responds to the pulses.

55 The dial at the subscriber's station may now be operated to connect the subscriber through the primary line finders and secondary line finders 105 and 109 to the operator's printer set 111. The subscriber may likewise be connected through a tollboard jack or a repeater control 60 unit for local exchange service, as described in my Patent 1,895,113 or the Hallden Patent 1,895,-097. As this particular connection is not needed for an understanding of my invention as disclosed herein, illustration thereof has not been 65 made.

65 After connection has been established at the central office, positive potential from the central office is supplied to the line thus reversing the line current causing polar relay 51 to operate to 70 close contact 120 energizing control relay 39 and starting the station printer motor 41. The control relay also removes the short circuit from the keyboard contacts and printing magnet 43 and establishes a short circuit around the high 75

resistance winding 53 of polar relay 51 and the dial lamp 117. Calling key 113 should now be restored to the normal central position. Release of this circuit is controlled from the central office in the same manner as that described in connection with Fig. 3.

In the event the central station desires to be connected with a particular subscriber's line such connection is established by dialing from outward operator's printer such as 121 through selector 123 and connector circuit 125 to private and line bank contacts P₁, L₁, and through the line to the particular printer station, in the manner disclosed in my Patent No. 1,895,113.

If a local station-to-station call between two subscribers is desired after operating calling key 113 and waiting for dial lamp 117 to light, as described, one digit is dialed to select this class of service. This increases the line resistance at the selecting circuit to extinguish the dial lamp until the line is connected through the secondary finder to the repeater control unit at which time the dial lamp is again brightly lighted. Further operation of the dial controls selectors and connectors to extend the circuit to the called station line after which the calling key is restored to its normal center position. This reconnects the high resistance winding of the polar relay 51 into the line, reduces the line current to normal value and causes the repeater control unit to connect the calling and called station lines through a single line repeater connecting a positive potential to both lines.

This system is not illustrated herein but is fully set forth in the Hallden Patent No. 1,895,097.

The positive potential thus applied causes polar relays 51 at both the called and the calling station to operate their respective control relays 39 starting the motors 41 and increasing the line current to its normal working value, in the same manner as set forth above in the description of the circuit of Fig. 6.

To release these connections the calling key at the subscriber's station may be operated to its clear out position, to the left as shown in Fig. 6. This opens the contact 127 removing the short from clear out relay 129 and allowing it to operate in series with control relay 39. The clear out relay locks itself in operated position through contacts 131 and establishes a short circuit around control relay 39 which then releases stopping motor 41 and reducing the line current again to the normal non-operating value. This low current permits a slow acting relay, not shown, associated with the single line repeater, not shown, to release the connection. Current from a negative battery on the line then operates through polar relay 51 releasing the clear out relay and restoring the circuit to normal.

The high current circuit, such as shown in Fig. 4, may be used in substantially the same manner for local exchange service. For adapting this system to such service a resistance 20, of substantially the same resistance value as high resistance 53 of polar relay 51, is shunted across calling key 21. After operating calling key 21 and receiving the usual indication in meter 103, one digit is dialed on dial 101 to select the local exchange service. Calling key 21 is then operated to reduce the line current by reinserting resistance 21 in circuit, causing the repeater control unit to connect the calling and called station lines through a single line repeater, connecting a positive potential to both lines. When the positive potential is applied to line 3 current reverses

in meter 103. The subscriber then releases calling key 21 and circuit is established in the manner described above.

Release of this connection may be accomplished by manipulation of key 21, to reduce the line current to a low value as described above. This drop in current permits the slow acting relay associated with the single line repeater to release, opening the line connection. The circuit at subscriber's station then returns to its normal un-operated condition in a manner similar to that described in connection with Fig. 1.

In an automatic concentration system of either of the types described, during periods of heavy traffic all of the printer sets at the central office for receiving or sending telegrams and their associated automatic switches may be busy, with the result that incoming calls or outgoing messages may be delayed. Additional printer sets can be provided, but if these are connected in the usual way additional automatic switching equipment must also be provided. This involves a considerable expense for equipment that is only used for a comparatively short time each day. During such periods, certain subscribers' stations will have enough traffic to keep a central office printer continually busy, or nearly so, and it is, therefore, desirable to "table" them or, in other words, to connect them directly with certain central office printer sets. There is no need for rapid switching on such connections, as they are set up and left connected for fairly long periods of time. Arrangements are provided, therefore, for making these connections with cords and jacks to avoid the expense of providing automatic switches. As there may be some idle periods, even during busy hours, on such circuits it is desirable to equip them with calling and motor control arrangements.

To take care of such cases, a group of central office printer sets is provided, each set being connected as shown in Fig. 7. Each line circuit, as shown in Figs. 1 and 4, has a line jack 200 for use with cords such as 201 of the "tabling" printers. When it is desired to "table" a particular line, a cord 201 is plugged into the line jack 200. The extra contacts on the jack ground the P bank contacts, making this line test busy to all outgoing calls, and operating both the line relay and the cut-off relay. The subscriber's line 3 is now disconnected from its regular line and cut-off relay and connected to relays 11 and 23 associated with the "tabling" printer set shown in Fig. 7.

If the subscriber's station is of the normal low current type, as shown in Fig. 3 or Fig. 6, relays 11 and 23 will remain released when the cord is plugged in. To call, the subscriber operates his calling key in the usual way, thus increasing the line current and operating relay 23. Relay 23 locks itself through release key 203 and operates relay 11. The line is now connected through the B contacts of relays 11 and 23 to the central office printer. Relay 23 also operates control relay 39 and lights the guard lamp 209 to call the central office operator's attention to the call. The control relay connects positive battery to the central office printer motor, starting it, and to the line, starting the subscriber's printer motor in the usual way. The subscriber may now send his message.

To release the connection, the operator depresses release key 203, releasing relay 23 which connects negative battery through its A contact and the winding of relay 11 to the line. A guard

5 lamp is extinguished and the control relay is released at this time. The negative battery on the line stops the subscriber's printer motor in the usual way and cuts in the high resistance winding of relay 51, which releases relay 11, restoring the circuit to normal.

10 To call the station, the central office operator depresses call key 205 to operate relays 11 and 23, after which the circuit functions the same as during an inward call. In the case of a high current line, relay 11 remains operated after the call is released, and the relays function in the same manner as the usual line and cut-off relays for calling.

15 20 The remaining features of the system are substantially similar to those illustrated in Figs. 1 and 4 and need not be described in detail. The circuit connections of this printer may be readily followed by a reference to the particular description made in connection with the other figures.

25 While the description given above refers generally to a single subscriber's station and its connection with the central office, it is, of course, understood that in a system of automatic printing telegraphy, such as described, any desired number of subscribers may be connected to the central operator's station in the usual manner.

30 35 While my invention has been described with particular reference to the attached drawings, such description is not intended as a limitation thereon. My invention and the particular features for which I desire protection are defined in the appended claims.

35 What I claim is:

1. In a printing telegraph system, a subscriber's station, a central office, a line circuit from the subscriber's station interconnecting said station and office, means at the central office for establishing connection between the subscriber's line circuit and an idle printer at said central office, and means operative alternatively in response to an increase, or a decrease and a subsequent increase in normal line current for operating said first named means.

2. In a printing telegraph system, a plurality of subscribers' stations, a line from each subscriber's station to a central office, means at the central office for connecting said subscribers' stations to an idle printer, and means operative alternatively in response to a breaking of said subscriber's line circuit and subsequent closing of said line, or to increased current on said line circuit for operating said connecting means.

3. A printing telegraph system as claimed in claim 1, further comprising a release key and means operative upon manipulation of said release key to restore said system to its original state.

4. In a printing telegraph system, a subscriber's station, a subscriber's printer, a central office, a printer and a finder switch at said central office, a line connecting said subscriber's station to said central office, means operative alternatively in response to an increase, or a decrease and subsequent increase of current in said line current to operate a selecting means, means responsive to operation of said selecting means to connect said line to said central printer, and means responsive to said last named connection, to operate said subscriber's printer.

5. In a telegraph concentrator circuit, a cut-off relay, a line relay, line windings on said relays connected with a source of current, other windings on said relays connected with a source of

current and normally in an open circuit, means responsive to a change in line current to change the current through said line windings, and means responsive to said change in current to close the circuit through said other windings on both said relays.

6. In a line relay circuit, a line relay, a cut-off relay, windings on said relays, a line circuit normally closing said cut-off relay winding and normally leaving said line relay winding open circuited, other windings on said cut-off and line relays, said last named relay windings being normally open circuited, means responsive to opening and closing of said line circuit to open said normally closed relay winding and close said normally open relay winding, and means responsive to the closing of said normally open winding to close the circuit through said other relay windings.

7. In a line relay circuit as claimed in claim 6, means for opening said second named relay circuit, and means responsive to the opening of said circuit to restore the circuit to normal.

8. In a line relay circuit, a line relay, a cut-off relay, windings on said relays, a line circuit normally connected through said line relay windings, the current in said line circuit being normally insufficient to operate said relays, other windings, normally open circuited, on said cut-off line relays, and means responsive to an increase of current in said line to close the circuit through said last named windings.

9. In a printing telegraph exchange system, a subscriber's station, comprising a polar relay, a motor control relay and a calling key, a line connected to said subscriber's station, a line relay circuit, comprising a slow release cut-off relay, a line relay and a group relay, means operative upon operation of said calling key to cause said line relay to operate said group relay, selective means operative upon energization of said group relay to connect said relay circuit to a central office printer, local windings on said cut-off and line relays, means responsive to said last named connection to energize said series windings, and means responsive to energization of said local windings to connect said line to said central office printer and to release said motor control relay.

10. In a printing telegraph system, a subscriber's station, a central office, a line from said subscriber's station to said central office station, a printer set at said central office, a line control relay circuit operative alternatively in response to an increase, or a decrease and a subsequent increase of normal current in said line for controlling the establishing of a circuit between said subscriber's station and said printer set, and means for connecting said printer set directly into said line.

11. In an exchange system, a station connected over a normally closed line with a central office, a source of line current at said central office, a cut-off relay at said central office normally energized by said line current, a normally deenergized line relay at said central office, means at said station for momentarily decreasing said line current to release said cut-off relay and to energize said line relay to initiate a call at said central office, means responsive to said call to energize both said relays and means responsive to the release of said call to release said line relay.

12. In an automatic printing telegraph exchange system, a plurality of stations connected over single wire lines to a central office, relays in

each line at the central office for controlling automatic switches, said relays being provided with means operative, alternatively by increasing the line current above normal, or by first decreasing the line current below normal for operating said automatic switches and then increasing it to normal.

- 5 13. In a printing telegraph exchange system, a plurality of subscribers' stations, a central office, a line from each subscriber's station to said central office, printer sets at said central office, means for connecting anyone of said printer sets directly into any one of said lines, and relay means in said printer set, operative alternatively in response to a decrease below normal and subsequent increase to normal or to an increase above normal of the line current to establish communication between said subscriber's station and said central office.
- 10 14. In an automatic exchange system, a plurality of subscribers' stations, a central office, line circuits from said subscribers' stations to said central office, means at said central office for communicating with said subscribers, a source of line current at said central office, and means in each subscriber's line operative alternatively
- 15 20

in response to increase in line current, or a decrease and subsequent increase to normal of said line current to establish connection between the subscriber's station and the central office communicating means.

5 15. In an automatic telegraph exchange system, a cut-off relay, a line relay, line windings on said relays, a source of current for said line windings, means responsive to a change in current in said line windings to change the current through said windings, normally open circuited local windings on said relays, and means responsive to said change in current in said line relays to close the circuit through said local windings.

10 16. In an automatic exchange system, a station connected over a normally closed line with a central office, a source of current at said central office, a line relay and a cut-off relay at said central station normally in circuit with said source, means at said station for increasing said line current above normal, means responsive to said increase in line current to open said cut-off relay circuit to initiate a call, and means operative in response to initiation of said call to energize other windings on said relays.
